UNITED STATES PATENT OFFICE.

EDWARDS F. SCHERMERHORN, OF BROOKLYN, NEW YORK, ASSIGNOR TO THE RAIL JOINT COMPANY, OF NEW YORK, N. Y., A CORPORATION OF NEW YORK.

INSULATED RAIL-JOINT.

1,142,632.

Specification of Letters Patent.

Patented June 8, 1915.

Application filed January 25, 1915. Serial No. 4,298.

To all whom it may concern:

Be it known that I, EDWARDS F. SCHERMERHORN, a citizen of the United States, residing at Brooklyn, in the county of Kings 5 and State of New York, have invented certain new and useful Improvements in Insulated Rail-Joints, of which the following is a specification.

This invention relates to insulated rail joints, and particularly to an improvement 10 therein which provides means for thoroughly insulating the joint without employing rail-head insulating material for either rail.

15 A distinctive object of the present invention is to provide a construction and arrangement of parts whereby each joint bar shall be in electrical or metallic contact with the head of one rail, and shall have an air-gap insulation from the head of the other rail, thereby entirely avoiding the use of insulating material at the places most subject 20 to wear, and consequently materially increasing the life of the joint as an insulator.

25 It is proposed to embody these novel features in a form of construction admitting of the use of conventional joint bars of uniform section throughout, thus making the production of such bars the usual rolling 30 mill proposition.

35 A further object of the invention is to utilize the uniform joint bars in combination with a distribution of insulating material along the base flange portions of both rails so as to provide uniformity of flexibility throughout the joint, as well as maintaining a complete insulation for the entire base flange portion of the joint.

40 In carrying forward these objects, the essential features of the invention may be embodied in different forms of construction and applied to various kinds of joints without departing from the scope thereof, but a specific form of construction best exemplifying the invention is shown in the accompanying drawings, in which—

45 Figure 1 is a side elevation of an insulated rail joint constructed in accordance with the invention. Fig. 2 is a side elevation thereof 50 with the joint bar removed to expose the

preferable form of insulation employed. Fig. 3 is a vertical cross sectional view of the joint on the line 3—3 of Fig. 1, that is, through the completely insulated end of the joint. Fig. 4 is a similar view through the 55 receiving-rail end of the joint on the line 4—4 of Fig. 1.

Similar reference characters designate corresponding parts throughout the several figures of the drawings.

Different forms of construction, involving different types of rail joints and of splices, 60 may be employed to maintain the air-gap insulation for one portion of the head of a joint bar and an electrical contact or communication between the remaining portion of the head of said bar and one rail, but the joint construction selected for illustration will clearly exemplify the features of novelty claimed. Referring to this illustrated embodiment of the invention, the rail joint shown includes the separate rails 65 1 and 2, which are respectively the leaving rail and the receiving rail, a pair of oppositely arranged joint bars 3, and the usual 70 joint bolts 4.

75 Each joint bar may be formed in any suitable manner, preferably by the usual rolling operations, but according to the present invention the bar is of uniform section and height throughout, that is, the structural and dimensional characteristics of the bar are uniformly preserved from end to end thereof. However, in order to fulfil the requirements of the invention, in combination 80 with the other related parts, the distinctive feature of improvement in the construction of the bar resides in forming the same with an upright member 5 so made that the head portion 6 thereof, at 7, is spaced a sufficient distance from the under sides of the rail heads to form an insulating air gap to take the place of the usual rail head insulating member commonly used.

85 Accordingly, in the specific form and application of the invention shown, by reason of the spacing of the top edges 7 of the joint bars from the under sides of the head of the leaving rail, an electrically insulating air-gap 8 is provided, at these points, as 90 95 100

plainly shown in Figs. 1 and 3 of the drawings, said air-gap effectually preventing electrical communication between the top edge of the upright member 5 and the head of 5 the leaving rail.

To compensate for the space which provides the air-gap insulation for one portion of the head of the joint bar, a metal angle 10 filler-plate 9 is interposed between the remaining portion of the bar and one rail of the joint, preferably the receiving rail, thus providing a rigid metal to metal bearing or electrical contact between the joint bar and the head of the receiving rail. It is by reason 15 of this structural feature, in combination with the maintenance of the insulating air-gap 8, that the usual rail-head insulating material may be dispensed with, while at the same time the requisite stiffness 20 and strength for the joint is preserved.

The insulation of the joint described may be accomplished in a thorough manner by confining the insulating material to one of the rail ends. A preferable and practical 25 way of doing this resides in employing side insulation plates 10 interposed between the web of the leaving rail and the upright members 5 of the joint bars. Each side insulation plate 10 is preferably continued at 30 its upper edge to a point at or slightly above the top edges 7 of the joint bars, as shown in the drawings, and it will be here observed that each of the joint bars is provided along the inner side of its head portion 6 with an 35 inwardly projecting inside abutment rib 11 adapted to contact with the adjacent edge portions of the insulation plate 10. This provides a clamping or holding means for the side insulation at this point, and also 40 provides a bracing or holding point for the upper edges of the upright members 5, so that the latter may be clamped tightly in place and the joint bolts kept tight. In connection with this feature of the invention, 45 it will be observed that the metal filler plates 9 may be somewhat thinner than the insulation plates 10, so as to provide a clearance space 12 between the inner side of the head 6 of the bar and the skirt of the filler 50 plate or from the web of the rail. This clearance for the inner side of the head portion of the bar which is in electrical contact with one of the rail heads is for the purpose of permitting of the usual adjustments 55 of the bar to maintain the tight fit thereof upon the rails.

In the insulation shown, the side insulation plates 10 are provided with base insulation plates 13 in the form of cuffs or 60 sleeves embracing the rail base flanges. These base insulation plates 13 are preferably coextensive with the length of the joint so that they will not only cover and insulate the flanges of the leaving rail, but will

also cover the flanges of the receiving rail. 65 This form of construction safeguards the insulation of the joint throughout at the base and at the same time performs the desirable mechanical function of cushioning extensions (13^a) which relieve the rigidity 70 and stiffness of the non-insulated metal-to-metal construction at the receiving rail end of the joint, thus providing uniformity of flexibility throughout the joint without sacrificing any of the requisite stiffness and 75 strength thereof.

The joint insulating expedients illustrated in the drawings also include an end post 14 between the meeting ends of the rails and suitable bolt insulation, as for instance the insulating sleeves and washers 15 and 16 associated with the head and nut portions of the bolts which extend through the leaving rail and the upright member 5 of the bars. In this type of bolt insulation, metal 85 backing washers 17 are usually interposed between the heads and nuts of the bolts and the insulating washers 16.

Various modifications of the invention may be resorted to without departing from the spirit or scope thereof, and in that connection it will of course be understood that the insulation plates may be in separate pieces instead of integral, and that the improvement may be readily adapted to staggered or cross insulation wherein the bars and the insulation at opposite sides of the rails have a reversed relation. This will be apparent to those familiar with the art without illustration, as well as the fact that changes in the form, proportion, and minor details of construction may also be resorted to without departing from the spirit or sacrificing any of the advantages of the invention. 105

I claim:

1. An insulated rail joint including, in combination with the rails, a joint bar of uniform section throughout in electrical communication with the head of one rail and having an air-gap insulation from the head of the other rail. 110

2. An insulated rail joint including, in combination with the rails, a joint bar of uniform height throughout in electrical communication with the head of one rail and having an air-gap insulation from the head of the other rail. 115

3. An insulated rail joint including, in combination with the rails, a joint bar of uniform height throughout in electrical communication with the head of one rail and having an air-gap insulation beneath the head of the other rail, and insulating material between the bar and a rail. 120

4. An insulated rail joint including, in combination with the rails, a joint bar of uniform height throughout in electrical

communication with the head of one rail and having an air gap insulation beneath the head of the other rail, and insulating material between the bar and the flange of 5 the latter rail.

5. An insulated rail joint including, in combination with the rails, a joint bar of uniform height throughout in electrical communication with the head of one rail and having an electrically insulating air-gap spacing from the head of the other rail, and electrical base insulation extending along both rails.

15 6. An insulated rail joint including, in combination with the rails, a joint bar of uniform height throughout in electrical communication with the head of one rail and having an electrically insulating air-gap spacing from the head of the other rail, and electrical insulation for the base of both rails.

7. An insulated rail joint including, in combination with the rails, a joint bar having an upright member of uniform height throughout, a portion of the head of said bar being in electrical communication with the head of one rail, and the balance of the head of said bar having an electrically insulating air-gap spacing from the head of the other rail.

30 rail.

35 8. An insulated rail joint including, in combination with the rails, a joint bar having an upright member of uniform height throughout, a portion of the head of said bar being in electrical communication with the head of one rail, the balance of the head of said bar having an electrically insulating air-gap spacing from the head of the other rail, and insulating material at the side of

40 the joint bar.

9. An insulated rail joint including, in combination, the rails, a joint bar having an air-gap insulation between its top edge and the head of one rail, a metal filler between the head of the bar and the other rail, and insulating material at the side of said bar.

10. An insulated rail joint including, in combination, the rails, a joint bar having an air-gap insulation between its top edge and the head of one rail, a metal filler between the head of the bar and the other rail, and insulating material at that side of the bar having the air-gap insulation.

11. An insulated rail joint including, in combination, the rails, a joint bar of uniform height throughout having an air-gap insulation between its top edge and the head of one rail, a metal filler between the head of the bar and the other rail, and insulating material at the side of said bar.

12. An insulated rail joint including, in combination, the rails, a joint bar of uniform height throughout having an air-gap insulation between its top edge and the head

of one rail, a metal filler between the head of the bar and the other rail, and insulating material at that side of the bar having the air-gap insulation.

13. An insulated rail joint including, in combination, the rails, a joint bar of uniform section throughout and having a truncated upright member spaced from the head of one rail to leave an intervening insulating air-gap, a metal filler between the head of said upright member and the other rail, and insulating material between the joint bar and a rail. 70 75

14. An insulated rail joint including, in combination, the rails, a joint bar of uniform section throughout and having a truncated upright member spaced from the head of one rail to leave an intervening insulating air-gap, a metal filler between the head of said upright member and the other rail, and insulating material between the joint bar and both rails. 85 80

15. An insulated rail joint including, in combination, the rails, a joint bar having an air-gap insulation between its top edge and the head of one rail, an insulating member 90 between said joint bar and said rail, and a metal filler between the head of the joint bar and the other rail.

16. An insulated rail joint including, in combination, the rails, a joint bar of uniform height throughout having an air-gap insulation between its top edge and the head of one rail, an insulating member between said joint bar and said rail, and a metal filler between the head of the joint bar and the other rail. 95 100

17. An insulated rail joint including, in combination, the rails, a joint bar of uniform section throughout having an electrically insulating air-gap spacing from the head of one rail, an insulating member between said joint bar and said rail, and a metal filler between the head of the joint and the other rail, said filler being thinner than the insulating member. 110

18. An insulated rail joint including, in combination, the rails, a joint bar of uniform section throughout having its head portion in electrical communication with the head of one rail and spaced from the web of that rail for adjustment purposes, said head portion of the bar having an air-gap spacing from the head of the other rail, and an insulating member between the said joint bar and the latter rail, said insulating member being engaged by the head portion of the bar.

portion of the rail. 125

19. An insulated rail joint including, in combination, the rails, a joint bar of uniform section throughout having an electrically insulating air-gap spacing from the head of one rail, an insulating member between the said joint bar and said rail, and

a metal filler between the head of the joint and the other rail, that portion of the metal filler next to the rail web being thinner than said insulating member to provide an adjustment clearance.

20. An insulated rail joint including, in combination with the rails, a joint bar of uniform fishing dimensions throughout, in electrical communication with the head of one rail and having an air gap insulation from the head of the other rail.

21. An insulated rail joint including, in combination with the rails, a joint bar having an upright member of uniform height

throughout, a portion of the head of said bar being in electrical communication with the head of one rail, the balance of the head of said bar having an electrically insulating air-gap spacing from the head of the other rail, and an insulating member between the joint bar and the web of the latter rail.

In testimony whereof I hereunto affix my signature in the presence of two witnesses.
